Albert Schwartz, Philadelphia, Pa., assignor to
Globe Rubber Products Corporation, Philadel-
phia, Pa., a corporation of Pennsylvania

Application August 21, 1952, Serial No. 21,140

Term of patent 14 years

(Cl. D9—6)

To all whom it may concern:

Be it known that I, Albert Schwartz, a citizen of the United States, residing in Philadelphia, county of Philadelphia, Commonwealth of Pennsylvania, have invented a new, original, and ornamental Design for a Rubber Mat, of which the following is a specification, reference being had to the accompanying drawings, forming a part thereof.

Figure 1 is a plan view of one side of the rubber mat, showing my new design.

Figure 2 is a plan view of the reverse side of the mat of Figure 1.

Figure 3 is a front elevation of the mat as shown in Figure 1.

I claim:

The ornamental design for a rubber mat, as shown.

ALBERT SCHWARTZ.
